TENSION EQUALIZER FOR SPINNING FRAMES

Earnest D. Meadows, Huntsville, Ala.

Application June 20, 1935, Serial No. 27,602

9 Claims. (Cl. 118—48)

The present invention relates to textile machinery and more particularly to spinning or twister frames.

Machines of this character, as commonly employed, comprise a central driving cylinder, with the spindles arranged on both sides thereof, and a driving band passing around said driving cylinder and a plurality of spindles.

It is necessary to provide means for taking up the slack in this driving band so that a uniform and equalized tension throughout all runs of the band is maintained.

The general object of the present invention is to provide an improved tension equalizer having means by which it may be universally adjusted so as to meet the requirements of any and all conditions which may arise.

A further object is to provide a universally adjustable tension equalizer of this character in the nature of an attachment which may be easily and readily applied to existing spinning and twister frames without the necessity of altering the construction thereof.

In order that the invention may be readily understood, reference is had to the accompanying drawings, forming part of this specification, and in which:—

Fig. 1 is a transverse section through a typical spinning and twister frame showing my improved tension equalizer applied thereto;

Fig. 2 is a fragmentary plan view of the same;

Figs. 3 and 4 are respectively a side and edge view of my improved equalizer attachment, the same comprising an idler pulley and an arm on which said pulley is mounted;

Fig. 5 is a longitudinal sectional view through the arm and pulley constituting my improved equalizer, and showing the method of attaching the same to the spindle rail of the frame; and

Fig. 6 is a transverse section on the line 6—6 of Fig. 5, looking in the direction of the arrows.

Referring to the drawings in detail, the usual spinning and twister frame comprises a plurality of "samps" 1, connected at each side by longitudinally extending spindle rails 3 and 4. Extending horizontally and centrally through the frame is a power or driving cylinder 2, mounted in suitable bearings (not shown).

Journalled in bearings 5 carried by the spindle rails 3, and disposed at each side of the machine are a series of spindles 6 each having secured thereto a driving pulley or whorl 7.

Passing around the driving cylinder 2 and the whorls 7 of a plurality of spindles is a driving band 8. As shown in the drawings, a single band

such as 8 drives a group of four spindles, and it will be understood that there are a number of such groups mounted in the frame.

By reference to Fig. 2, it will be seen that the driving band 8 is looped around the cylinder 2 three different times, as indicated at a, b and c. The idler pulley forming part of my improved tension equalizer is indicated at 9 in Fig. 1, and by reference to this figure, it will be seen that the band 8 includes a fourth loop d, which extends around this idler pulley.

Referring now to Figs. 3 to 6, inclusive, it will be seen that my improved idler pulley 9 is journalled by means of a bearing 17 on a pin or bolt 10, which is secured to one end of an arm 11, shown as formed of a pair of metal strips. The other end of this arm is pivotally connected by means of a pin 12 to one leg of an angle bracket 13, the other leg of said bracket being provided with an elongated slot 14 adapted to receive a bolt 15 for securing it to one of the spindle rails such as 4.

In order that the length of the arm 11 may be varied as required to meet different conditions, the arm is provided with a plurality of holes 16, through any one of which the pivot pin 12 may extend.

Secured to the end of the arm adjacent the pulley 9 is a weight 18. This is carried by a plate or bracket 20 having flanges at its edges which embrace the edges of the arm 11, and provided with an elongated slot 20 through which the bearing pin or bolt 10 passes, as clearly shown in Fig. 3. By loosening the nut on the bolt 10, the plate 19 carrying the weight 18 may be adjusted longitudinally of the arm and then clamped in adjusted position by tightening the nut again. Furthermore, by unscrewing this nut, the weight 18 may be detached entirely, or its position may be reversed from that shown in Fig. 3, to that illustrated in Fig. 5. By this means, the distance of the weight 18 from the pivot 12 may be adjusted as required, so that different degrees of tension may be applied to the band, as desired. Furthermore, I contemplate providing a set of interchangeable weights of different values, any suitable one of which may be selected and attached to the arm, in accordance with conditions.

The method of mounting the arm 11 on the spindle rail 4 by means of the slotted bracket 13 and bolt 15 constitutes an important feature of my invention. By virtue of this arrangement, it will be seen, from an inspection of Fig. 6, that not only may the arm 11 be adjusted longitudi-

nally of the spindle rail, but it may be swung about the bolt 15 as a pivot, to any desired angle, such, for example, as indicated in dotted lines in Fig. 6.

5 It will be understood, of course, that the arm 11 and pulley 9 can swing freely in their own planes about the pivot 12, the weight 18 serving to maintain the desired tension on the band. It is, however, usually desirable to set the plane 10 of the pulley 9 at an acute angle to the axis of the driving cylinder 2, and my improved construction permits of this pulley being set at any angle required or even completely turned through 180° and thus reversed. It will be noted that 15 this angular adjustment takes place around the bolt 15, the axis of which is parallel to the plane in which the arm and pulley swing.

In applying my improved attachment to existing spinning and twister frames, it is only necessary to bore a hole in the spindle rail to receive 20 the bolt 15. This hole can, of course, be placed at any desired point, and the bracket 13 carrying the pulley and arm may then be adjusted longitudinally and angularly to meet any existing 25 conditions. It will further be noted that the pivot 12 is at right angles to the axis of the bolt 15 so that, in fact, the pulley 9 is capable of universal adjustment.

What I claim is:

30 1. In a spinning or twister frame having a driving cylinder, spindle rails, spindles mounted on said rails, and a driving band extending between said cylinder and a plurality of said spindles, a tension equalizer for said band comprising 35 a weighted idler pulley around which the band is looped, an arm on which said pulley is mounted, and means for supporting said arm on one of said spindle rails for angular adjustment relative thereto about an axis laterally spaced from and 40 parallel with the plane of said pulley.

2. In a spinning or twister frame having a driving cylinder, spindle rails, spindles mounted on said rails, and a driving band extending between said cylinder and a plurality of said spindles, a tension equalizer for said band comprising 45 a weighted idler pulley around which the band is looped, an arm on which said pulley is mounted, and means for supporting said arm for swinging movement in its own plane, and 50 for angular adjustment about an axis parallel with and at one side of said plane.

3. In a spinning or twister frame having a driving cylinder, spindle rails, spindles mounted on said rails, and a driving band extending between said cylinder and a plurality of said spindles, a tension equalizer for said band comprising 55 a weighted idler pulley around which the band is looped, and means for adjusting the plane of said pulley to any desired angle relative to the axis of said cylinder, while maintaining the axis of said pulley parallel with a vertical plane 60 through the axis of said cylinder.

4. In a spinning or twister frame having a driving cylinder, spindle rails, spindles mounted

on said rails, and a driving band extending between said cylinder and a plurality of said spindles, a tension equalizer for said band comprising a weighted idler pulley around which the band is looped, an arm on which said pulley is mounted, 5 means for supporting said arm on one of said spindle rails for angular adjustment relative thereto about an axis at one side of and parallel with said arm, and means for varying the length of said arm.

5. An attachment for spinning or twister frames having a driving cylinder, spindle rails, and a driving band, said attachment comprising an idler pulley adapted to receive a loop of said band, an arm on which said pulley is mounted, 10 and means for supporting said arm on one of said spindle rails for angular adjustment about an axis laterally spaced from and parallel with said arm.

6. An attachment for spinning or twister frames having a driving cylinder, spindle rails, and a driving band, said attachment comprising an idler pulley adapted to receive a loop of said band, an arm on which said pulley is mounted, 15 means for pivotally supporting said arm for swinging movement in the plane of said pulley, and means for securing said arm to one of said spindle rails for angular adjustment about an axis located at one side of and parallel with said plane.

7. An attachment for spinning or twister frames having a driving cylinder, spindle rails, and a driving band, said attachment comprising an idler pulley adapted to receive a loop of said band, an arm on which said pulley is mounted, 30 a bracket to which said arm is pivotally connected, and means for securing said bracket to one of said spindle rails for angular adjustment with respect thereto about an axis at one side of said arm.

8. An attachment for spinning or twister frames having a driving cylinder, spindle rails, and a driving band, said attachment comprising an idler pulley adapted to receive a loop of said band, an arm on which said pulley is mounted, 45 and an angle bracket to one leg of which said arm is pivotally connected, the other leg of said bracket having an elongated slot adapted to receive a bolt by which said bracket may be secured to one of said rails.

9. An attachment for spinning or twister frames having a driving cylinder, spindle rails, and a driving band, said attachment comprising an idler pulley adapted to receive a loop of said band, an arm on which said pulley is mounted, 55 means for pivotally supporting said arm on one of said spindle rails, and a weight secured to said arm adjacent said pulley, said weight comprising a member having an elongated slot through which extends a clamping bolt, whereby 60 said weight may be readily detached or its position on said arm may be adjusted as desired, or reversed.

EARNEST D. MEADOWS.
